UNITED STATES PATENT OFFICE.

WILLIAM WALCH, OF ROCKWELL, IOWA.

MIXING DEVICE.

1,170,788.

Specification of Letters Patent.

Patented Feb. 8, 1916.

Application filed November 23, 1914. Serial No. 873,520.

To all whom it may concern:

Be it known that I, WILLIAM WALCH, a citizen of the United States, residing at Rockwell, in the State of Iowa, have invented certain new and useful Improvements in Mixing Devices, of which the following is a specification.

This invention relates to improvements in internal combustion engines and consists in using a part of the exhaust gases to mix with the explosive charge after it has left the carburetor.

The object of the invention is to use a portion of the exhaust gases to heat the explosive charge, to use some of these gases in the charge for the sake of economy of fuel, and to provide an additional supply of heated air to the charge after carburetion.

With these and other objects in view, the invention consists in the construction and arrangement of parts hereinafter described and particularly pointed out in the claims; it being understood, however, that I do not intend to limit myself to the details of construction.

The invention is illustrated in the accompanying drawing in which:

Figure 1 illustrates diagrammatically the side of an engine with my device applied thereto, and Fig. 2, shows a front view of the engine with my device attached thereto.

In the drawings, the numeral 1 indicates the diagrammatical representation of the engine to which my device is attached, 2 the exhaust thereof, and 3, a passage over the exhaust 2 and communicating therewith into which some of the exhaust gases will rise. This passage 3 is tapped by a downwardly extending pipe 4.

5 indicates the intake manifold or pipe of the engine, 6 the pipe leading from the carburetor 7 thereto adapted to carry the carbureted charge.

8 indicates the air intake of the carburetor 7 and 9, the gasoline feed pipe.

On the pipe 4 is a coupling 10, having a damper or cutoff 11 therein, operated by a hollow tube or pipe 12 leading to the dashboard 13 or other convenient place. This pipe 12 has a flexible but continuous connection at 14 so that rotary movement of the pipe 12 from the dashboard will operate the damper or cutoff 11. The tube or pipe 12 is hollow and the flexible connection 14 is continuous to permit air to be taken into the

pipe 12 at the dashboard as at 15 and conducted to the coupling 10 and introduced thereto. Over the end 15 of the pipe 12 is provided a lever 16 pivoted on the pipe 12 for controlling admission of air to the end 15 of the pipe and also as a ready means for rotating the pipe 12 enough to operate the cutoff 11 in the coupling 10. To the coupling 10 is secured a pipe 17 forming a continuation of the pipe 4 but larger than that pipe to accommodate the air taken in through the pipe 12. This pipe 17 connects with the intake pipe 6 at a point below where the carbureted charge enters it at 18, but as near thereto as possible.

The operation of the device is as follows: To start the engine, all air from the dashboard is first cut off by the lever 16 but the cutoff 11 is left open. In running, a part of the hot gases of the exhaust in the pipe 2 rise into the pipe 3 from which they flow down the pipes 4 and 17 and up the pipe 6, this latter because of the suction in that pipe. Thus when the carbureted charge from the carburetor enters the pipe 6, it does not meet a cold pipe where it condenses but instead strikes an upward moving column of hot gas from the exhaust. This absolutely prevents any condensation at that point besides assures the vaporization of any of the fuel that may have passed through the carburetor unvaporized. If on a hot day or after the engine has become thoroughly warmed up, this supply of hot gas may be stopped or lessened if desired by simply turning the lever 16 to the right or left, or, air may be mixed with these exhaust gases by pressing the lever 16 down. This supplementing of the carbureted charge with hot exhaust gas having some air mixed therewith not only causes more efficient operation of the engine but causes a marked saving of fuel. The complete vaporization of the charge assured by its striking the hot upward blast in the intake pipe 6 causes such perfect combustion in the explosions, that the engine can be throttled down to a much slower speed than formerly. Also the present invention enables the motor or engine to be run at a higher speed than formerly and with less friction.

What I claim is:

1. In a system of the class described, an intake pipe, an exhaust pipe, a connecting pipe between said pipes whereby a portion

of the exhaust gases may be conducted into the intake pipe, means for adding air to the gases while in this connecting pipe, and a carbureter on said intake pipe adapted to deliver its carbureted charge into said exhaust gases in the intake pipe.

2. In an automobile, the system of additional fuel mixing for the engine comprising an intake pipe, an exhaust pipe, a connection between said pipes whereby a portion of the exhaust gases may be conducted into the intake pipe, a cutoff in said connection,

an air-supplying pipe in said connection, a carbureter on said intake pipe adapted to deliver its carbureted charge into said exhaust gases therein, and combined means on the dashboard of the automobile for controlling said cutoff and said air-supplying pipe.

Signed at Rockwell, Iowa, this 17th day of November, 1914.

WILLIAM WALCH.
